UNITED STATES PATENT OFFICE.

BENJAMIN F. BEAVER, OF HUTCHINSON, KANSAS.

FLYING-MACHINE.

1,117,155.

Specification of Letters Patent. Patented Nov. 17, 1914

Application filed November 26, 1913. Serial No. 803,260.

To all whom it may concern:

Be it known that I, BENJAMIN F. BEAVER, a citizen of the United States, residing at Hutchinson, in the county of Reno, State of Kansas, have invented certain new and useful Improvements in Flying-Machines; and I do hereby declare the following to be a full, clear, and exact description of the invention, such as will enable others skilled in the art to which it appertains to make and use the same.

This invention relates to new and useful improvements in flying machines, and particularly those of the heavier-than-air type.

The primary object of the invention resides in the provision in an aeroplane of means whereby the supporting plane may be actuated to assume such position as to form a parachute, so that in case accident should occur, a parachute may be formed by the body of the machine whereby the operator may safely descend.

A further object of the invention resides in the provision in an aeroplane of the class described of means whereby that mechanism which is operated to adjust the planes to form the parachute, also serves to move the various planes so that the machine is enabled to maintain its equilibrium.

A still further object resides in the provision of an aeroplane of the class described, which is efficiently braced to form a strong and durable structure.

With these and other objects in view, the invention resides in the novel combination, formation and arrangement of parts to be more fully hereinafter described and illustrated in the accompanying drawings and particularly pointed out in the claims hereto appended.

Reference is had to the accompanying drawings wherein similar characters of reference designate corresponding parts throughout the several views, and in which:

Figure 1 is a perspective view of the machine, with its planes in normal relation, Fig. 2 is a central vertical longitudinal sectional view taken through the machine. Fig. 3 is a transverse vertical sectional view through the machine, and Fig. 4 is a perspective view of the machine with its wings folded to form a parachute.

Referring now more particularly to the accompanying drawings, 5 designates four corner uprights of the frame of the aeroplane. The tops of these uprights are con-

nected by the rigid supporting plane 6 and the lower end of the uprights are connected by the sills 7. Carried by the sills 7 are suitable flooring members 8 on which is mounted an engine 9. Extending from the flooring member to the top plane 6 is a central vertical standard 10 and journaled in a bracket 11 on this standard is a shaft 12 which extends outwardly of the aeroplane frame and carries at said outer end a propeller 13. This outer end of the shaft is journaled in a bearing 14 carried by arms 15 extending diagonally upward from the front sills 7. These sills also carry ground wheels 19 and a suitable seat 18 is carried by the flooring forwardly of the engine. The shaft is driven by a sprocket chain 16 trained around gears 17 on said shaft and on the shaft of the engine 9.

Pivoted secured to at 20 and disposed between the front and rear pairs of uprights 5 are front and rear elevators or lifting planes 21 and 22 respectively. These planes are of such size that they serve also as lifting planes and they are adapted to be swung in a direction indicated by the arrows in Fig. 2 so that they substantially close the front and rear ends of the frame. The lower portion of the front elevator is provided with an open-ended slot 23 which receives the propeller shaft 12 when the plane is folded. For swinging these planes, a shaft 24 having fixed thereto a drum 25 is journaled in suitable brackets 26 disposed forwardly of the seat 18. Pulleys 27 are carried by the front and rear ends of the plane 6 and pulleys 28 are carried by the front and rear ground sills. A pulley 29 is also carried by the intermediate portion of the standard 10. A cable member 30 is secured to the rear end of the rear elevator 22 and is trained under the rear pulley 28, over the pulley 29 and over a pulley 27 and is secured to the forward end of the front elevator 21. The cable is then trained under the front pulley 28, wound around the drum 25, trained under the pulley 29 and over the rear pulley 27 and is secured to the rear end of the rear elevator 22. Thus upon rotation of the drum 25, the planes are simultaneously swung. To facilitate securing the cable to the forward lifting plane 21, it is split adjacent said frame to form the sections 30' which extend on each side of the slot 23.

Pivoted to the uprights 5 at points 31 dis-

posed above the pivotal connections 20 are ailerons 32 which are also of such size as to form supporting planes and which are adapted to be swung to close the sides of the frame. For swinging these planes a shaft 33 carrying a drum 34 is disposed adjacent and at right angles to the shaft 24 and is journaled in suitable brackets 35. The intermediate portion of the sides of 10 the top plane 6 carries pulleys 36 and the intermediate portions of the side sills 7 carry pulleys 37. A cable 38 is secured to the outer edge of one aileron 32 and extends under the adjacent pulley 37 and is wound 15 around the drum 34 from whence it extends and is trained around the other pulley 37 and secured to the inner edge of the other aileron. The cable is then trained around the pulleys 36 and has its end secured to the 20 outer edge portion of the first-mentioned aileron.

From the foregoing it is observed that upon rotation of the drum, in either direction the plane 32 will be swung simultaneously to maintain the lateral equilibrium of the machine. Upon rotating the drum in a clockwise direction it is observed that the planes 32 will swing in a direction indicated to close the sides of the machine.

30 The shafts 24 and 33 are provided with crank handles 39 and it is observed that by simultaneously rotating these crank handles, the planes 21 and 22 and the planes 32 will be swung to form with the rigid plane 6 a parachute whereby the machine and operator may safely descend. The crank handles also control the planes in their normal operation.

To brace the planes 32 in such manner as 40 to not interfere with their swinging movement, the central portions thereof are cut away at 39 and extending across said portions are shafts 40. Brace bars 41 are provided which have their upper ends inwardly 45 directed at 42 and secured to the sides of the rigid plane 6 and have their lower ends inwardly directed at 43 and pivotally con-

nected to the shafts 40. Guy wires 44 are extended from the uprights 5 to the upper portions of said brace bars.

From the foregoing it is observed that an aeroplane has been provided which is strong and durable and readily controlled in its normal operation and which has its movable planes so mounted that they may be readily swung to form a parachute.

It is not desired to limit this invention to any of the details of construction shown and described, as it will be understood that various minor changes and modifications within the scope of the appended claims may be made without departing in any manner from the spirit of the invention.

What is claimed is:

1. An aeroplane comprising corner uprights, a top plane connecting the upper ends of the uprights, sills connecting the lower ends of the uprights to form a frame, a propeller shaft carried by the frame and extending outwardly of one end thereof between a pair of end uprights, elevator planes pivoted between the pairs of end uprights, means for swinging said planes and the plane adjacent the propeller shaft being provided with a slot for receiving the propeller shaft upon swinging the planes.

2. In an aeroplane, the combination with a frame including a pair of uprights and a top member connecting the uprights, of a plane disposed between and pivoted to the uprights and provided with a central cut-away portion, a shaft carried by the plane and extending across the cutaway portion and a brace bar having its upper end inwardly directed and secured to the top member and having its lower end inwardly directed and pivoted to the shaft.

In testimony whereof, I affix my signature, in the presence of two witnesses.

BENJAMIN F. BEAVER.
